Primary Examiner — Carla Jobe Wright(74) *Attorney, Agent, or Firm* — Rutan & Tucker LLP; Hani Z. Sayed(57) **CLAIM**

The ornamental design for cell phone case with loop, as shown and described.

DESCRIPTION

FIG. 1 is a front, left side, bottom perspective view of the present invention;

FIG. 2 is a front elevation view of the present invention;

FIG. 3 is a left side elevation view of the present invention;

FIG. 4 is a right side elevation view of the present invention;

FIG. 5 is a rear elevation view of the present invention;

FIG. 6 is a top plan view of the present invention, the bottom plan view being a mirror image of the top plan view; and,

FIG. 7 is an enlarged sectional view of the present invention taken along line 7-7 of FIG. 2.

The broken lines in FIG. 1 depict an unclaimed cell phone.
